UNITED STATES PATENT OFFICE.

CHARLES A. DALLY, OF MOON, PENNSYLVANIA, AND HARRY K. RICHARDSON, OF DETROIT, MICHIGAN.

GAS REGULATOR AND CUT-OFF.

SPECIFICATION forming part of Letters Patent No. 374,779, dated December 13, 1887.

Application filed March 14, 1887. Serial No. 230,755. (No model.)

To all whom it may concern:

Be it known that we, CHARLES A. DALLY, of Moon township, Allegheny county, Pennsylvania, and HARRY K. RICHARDSON, of Detroit, Wayne county, Michigan, have invented 5 a new and useful Improvement in Gas Regulators and Cut-Offs, which improvement is fully set forth in the following specification, reference being had to the accompanying drawing.

10 Similar letters of reference indicate corresponding parts.

The object of our invention is a gas-regulator arranged to automatically cut off the flow of gas after it has once fallen below a fixed 15 pressure or on a total failure of supply occasioned by accident or otherwise.

The drawing accompanying this specification, and made part thereof, is a cross and longitudinal section of our device.

20 A is what we choose to call the "high-pressure chamber," and A' the "low-pressure chamber."

B is a diaphragm. b is the upper half of the diaphragm-disk, and b' the lower half.

25 b² is an air-aperture.

C is a flexible diaphragm, and it is secured to the flange c² of the chamber B by bolts in the usual way.

30 c is a metallic disk which we use in connection with said diaphragm for support and attachment purposes.

D is a lever fixed to the post D' at d'.

d is an adjustable weight on the lever D.

To the lever D is fixed a rod, E, at d². This 35 rod passes down through the diaphragm-chamber B, and is fixed to the diaphragm itself at e by any suitable means. This lever E goes on down through the part B' and into the chamber A', where it is secured to the lever F at e'.

40 F' is a fulcrum for the lever F. This latter-named lever extends from said fulcrum F', by another arm, f', to the valve-rod F², being secured thereto at f². The valve-rod F² is secured to the valve G at the upper end thereof.

45 The valve G is round in form, is closed at the bottom and top, and has several inlet-ports, g', and outlet-ports g, and at the base has a beveled flange, g², forming, in connection with the walls of the chamber A, a valve-seat.

50 H' is a plug in the opening to the valve-

seat in the chamber A' from above, and H is a plug in the opening to the valve-seat and chamber A from below. These openings H and H' serve to adjust and regulate the valve in its place.

55

It will be readily seen that by lowering the valve G a short distance the gas will pass into the lower ports, g', and will then pass out at the upper ports, g, into the chamber A', and that when the valve is raised up into its seat 60 closely all further flow of gas will be shut off until the lever D is again adjusted.

The flow of gas, when once cut off through our device, being checked, no danger can follow if the pressure in the pipes is renewed, 65 and that is the main object in view in our invention.

The required flow of gas by our device is regulated by means of our system of levers, valve, and diaphragm, as aforesaid. When 70 gas is admitted to the chamber A', it passes on up into the chamber B, where it exerts an upward pressure on the diaphragm itself, and by means of the weight d such pressure is fixed as required.

75

It will be seen that should there be a failure of gas-pressure on the diaphragm the lever D will descend, thereby pushing down on the valve-lever F, and consequently the valve itself will be drawn upward and closely into its 80 seat, thereby shutting off the flow of gas, and this status will be maintained by the gravity of the weight d on the lever D.

We are aware that it is not new to provide a pressure-regulator with a valve having connection with a diaphragm in a communicating chamber, and that such diaphragms have been connected with a weighted lever, and in some cases the diaphragms have been backed by a spring, whereby the valve may be entirely 90 closed under extraordinary pressure, and we therefore do not claim such constructions, broadly.

Having thus described our invention, what we claim, and desire to secure by Letters Patent, is—

95

The combination, in a gas regulator and cut-off, of the chambers A and A', having an intermediate beveled valve-seat, the valve G, constructed as described, having entrance and 100

exit ports g' and g and a beveled flanged edge adapted to set against the seat, the lever F, connected to said rod, and the whole arranged within the coupling-section, as shown, 5 the chamber B, connected with the removable chamber A, the diaphragm C, connected to lever F, and the weighted lever D, the whole arranged to regulate the flow of gas or cut chamber A off entirely when the pressure falls below 10 a certain point, substantially as described.

In testimony that we claim the foregoing as our invention we hereto set our hands in presence of two witnesses.

CHAS. A. DALLY.
HARRY K. RICHARDSON.
